UNITED STATES PATENT OFFICE.

WILLIAM H. J. FITZGERALD, OF BRAINTREE, MASSACHUSETTS.

WINDOW-SCREEN CONSTRUCTION.

1,426,561.

Specification of Letters Patent. Patented Aug. 22, 1922.

Application filed August 17, 1921. Serial No. 493,093.

To all whom it may concern:

Be it known that I, WILLIAM H. J. FITZGERALD, a citizen of the United States, and resident of Braintree, county of Norfolk, 5 State of Massachusetts, have invented an Improvement in Window-Screen Constructions, of which the following description, in connection with the accompanying drawing, is a specification, like characters on the 10 drawing representing like parts.

This invention relates to improvements in window construction, and one of the principal objects is to provide a novel construction in which a sliding sash can be readily removed and replaced.

A further object of the invention is to provide means for preventing the removal of the sash except when raised to a predetermined height from closed position.

Another object of the invention is to provide, as an article of manufacture, complementary runs of special construction, adapted to be secured to the frame and edges of the sash, so constructed as to permit easy removal of the sash.

A further object of the invention is to provide a novel knock down screen construction comprising permanently connected corners to which sides and ends of any desired 30 length may be secured, so that a customer purchasing the parts can construct a screen to fit any size of window frame.

A further object of the invention is to provide a novel means for securing the 35 foraminous screen in the sash which will enable it to be readily removed and replaced.

Other objects and features of the invention will more fully appear from the following description and the accompanying 40 drawings and will be particularly pointed out in the claims.

The drawings illustrate a preferred embodiment of the invention applied to a window screen construction, but it will be understood that the invention may be employed in connection with removable window sashes or panels or any other mechanisms to which it is adapted.

In the drawings:

Fig. 1 is an elevation of a window frame having a window screen embodying my invention slidably mounted therein.

Fig. 2 is a detail view of a preferred form

of locking device for retaining the screen in assembled position in the frame.

55

Fig. 3 is a perspective view of the retaining means illustrated in Fig. 2.

Fig. 4 is a perspective view of a preferred form of screen sash corner embodying my invention showing in dotted lines portions 60 of the connecting and filling members which complete the sash.

Fig. 5 is a vertical sectional view through one of the ends of the window screen embodying my invention.

65

Fig. 6 is a perspective view of a section of one of the recessed tongued runs for the window construction embodying my invention.

Fig. 7 is a perspective view of an assembled knock-down screen embodying my invention, certain of the screen retaining strips being omitted.

Fig. 8 is an end or side elevation of the sash construction embodying my invention 70 showing the corner sections and the connecting and filling members in full lines separated from said corner sections, but illustrating in dotted lines the connecting and filling members in assembled position.

80

A preferred embodiment of the invention is illustrated in the accompanying drawing as applied to a window screen slidably mounted in the window frame, but it will be understood that the invention may also be applied to one of both of the glass supporting sashes for the window. As illustrated in the drawing, the window frame comprises the usual sill 1, sides 2 and 3 and top 4 in which the window sashes are mounted.

85

The window screen, consisting of foraminous or reticulated wire or fabric, is mounted in a sash having ends 5 and 6 and sides 7 and 8 and may be of usual construction with my invention applied thereto, but preferably comprises a special knock-down structure which will hereinafter be more fully described.

90

In usual window screen constructions, the side members 2 and 3 of the window frame 100 are provided with tongued runs and the ends of the screen sash are provided with complementary grooved runs, which are slidably mounted upon said tongues, so that the window screen may be raised and lowered.

95

105 In the present construction, one of the side

members 2 may be provided with the usual type of run 9, having a tongue 10 extending continuously longitudinally thereof and the end 5 of the screen sash may have secured 5 to it a run 11 having a groove complementary to the tongue 10.

The opposite side 3 of the window frame desirably is provided with a run 12 having a tongue 13 provided with a plurality of recesses 14 spaced apart a predetermined distance, leaving portions 13^x of said tongue between said recesses. The lower recess desirably is located at a predetermined distance from the base or sill 1 of the window frame. The corresponding end of the screen sash is provided with a grooved run 15, one of the walls of said groove being cut away to provide recesses 16, which correspond in length and are complementary to the tongued portions 13^x intermediate of the recesses 14 in the tongue so that, when the recesses in the wall of the groove are placed opposite the portions 13^x of the tongue, the recesses 14 in the tongue will be opposite the remaining portions of the wall of the groove. When in this position, the sash can be swung laterally, preferably outwardly, the tongue 10 of the opposite end of the screen acting as a pivot about which the screen may be swung. 30 In the normal position of the screen sash, the tongued and grooved runs interengage in the usual manner, but when the sash is raised sufficiently to cause a registry of the remaining portions of the tongued and 35 grooved walls, the interengaging members may be disengaged in the manner aforesaid, and the screen may be readily removed and replaced.

In order to provide means for normally preventing such disengagement when the screen is raised, a removable member or members may be so placed as to fill one or more of the said recesses, and preferably to form continuations of the cutaway portions 40 of the run. A convenient device of this character is illustrated in Figs. 1, 2 and 3 and comprises a plate 17, which desirably has a flange 18 adapted to be so positioned as to form a continuation of the tongue 13 across one of the recesses 14 in the tongue 13. The plate 17 may desirably have a thumb piece 19, by means of which it may be manipulated, and desirably is provided with a hook-shaped end 20 adapted to engage a locking stud upon 45 the window frame.

The plate 17 may be sufficiently counter sunk in the wall of the run as not to interfere with the raising and lowering of the sash, as illustrated in Fig. 1. Preferably the plate 60 17 is pivotally mounted upon a base plate 17^a, which is counter-sunk into the run. The ends of the base plate 17^a desirably may extend into slots beneath the end portions of the tongue of the run adjacent the recesses 14 to secure the plate more firmly. When 65

the retaining member is in normal position, illustrated in Figs. 1 and 2, the flange 18 serves to close the recess 14 and to form a continuation of the run so that the sash will slide upwardly in the usual manner. When 70 it is desired to remove the sash, it is merely necessary to swing the retainer 17 about its pivot to the position illustrated in dotted lines in Fig. 2. Whereupon, the window sash may be raised until its recesses register 75 with the remaining portions of the tongue and the wall of the groove, then swung outwardly, as above described.

While the invention may be employed with runs of the usual character which have been 80 provided with suitable recesses, as above described, there may be spaces opposite the recesses through which flies and other insects might crawl into the room if greatest care is not exercised in constructing the recesses. 85 In order to prevent such apertures, special runs are provided, such as the tongued runs illustrated in Fig. 6, in which the thickness of the run at one side 22 of the tongue 13 is greater than the thickness of the run at the other side 23 of the tongue 13. The walls of the grooved run desirably are complementary in length to the sides 22 and 23 of the run, so that the walls of the groove and tongue will overlap and thereby prevent any opening through which the insects can enter the room. The complementary runs upon the other side of the window frame and sash 90 desirably are similarly constructed but without recesses, so that the shorter wall of the 100 groove will permit a more convenient pivotal movement of the sash when the screen is to be removed or replaced.

Screens made in accordance with the invention above described may be manufactured in complete form and suitably recessed runs sold with them for the purpose of installation in buildings. However, as windows vary greatly in size, both as to width and height, my invention contemplates the production of complementary runs as articles of manufacture which are adapted to be sold to the builder or owner of the house and applied to usual forms of window screen sash and window frames. 115 Thus, the tongued and grooved runs may be produced of any suitable length and provided with recesses of a predetermined length at predetermined distances apart, so that to equip a usual window frame and screen of any size with runs embodying my invention, it is merely necessary to saw the required length of runs and attach them respectively to the frame and the end or ends of the usual rectangular screen. 120

The invention further contemplates the production of a sash formed of sections so constructed that said sections may be cut and assembled to fit any size of window frame. In the preferred embodiment of the 130

invention illustrated herein, the sash comprises corners having end members 24 and side members 25, preferably secured together by a mitered tenon joint 26. The 5 ends of the end and side members 24 and 25 are provided respectively with recesses 27 and 28 adapted to receive the ends of connecting members 29 and 30 respectively. The connecting members may be merely 10 straight pieces of wood or other material of the same width as the end and side members 24 and 25 and of a thickness corresponding to the depth of the recesses 27 and 28. By securing the ends of these connecting 15 members to the corner members as aforesaid, a rectangular sash will be produced. Preferably fillers 31 and 32 may be inserted between the exposed portions 33 and 34 respectively of the end and side members 29 and 30 respectively.

20 A further feature of the invention consists in providing a novel and convenient mechanism for stretching the foraminous or reticulated screen and locking it in place in the sash. This is accomplished by providing 25 grooves 35, preferably in the outer faces of the end and side members of the sash, which are adapted to receive locking members 36, preferably of cylindrical form, and securing retaining strips over the 30 mouths of said grooves. If these grooves are cut directly into the outer faces of the sides and ends of the sash, the retaining strips will increase the thickness of the sash which will be somewhat unsightly. A preferred 35 construction is illustrated in Fig. 5 in which the outer face of the strip is provided with a shallow recess 37 having an undercut end wall 38 to receive the complementary beveled end of the retaining strip 39. The groove 35 extends downwardly 40 from the bottom of said recess and is located a short distance from the inner edge of the sash.

In assembling the screen, the foraminous 45 material may be placed upon the sash with its edges extending over the grooves; the cylindrical locking member may then be forced into the groove, thrusting the edges of the screen down into the grooves, as illustrated in Fig. 5. The retaining members 39 may then be inserted with their beveled edges beneath the undercut walls 38 of the recesses and secured to the sash by nails 40 or other suitable fasteners.

50 It will be readily understood that the knockdown screen, which is formed of assembled corners and connecting members, may likewise be provided with grooves to receive locking members and recesses for retaining strips in the manner above described,

the grooves preferably being formed in the connecting members 29 and 30 rather than in the faces of the fillers 31 and 32.

When the locking bars are thus forced into position, the screen is stretched very 70 tightly, so that the members of the screen in effect form trusses for the sash, which hold the sash members firmly in position and provide a very rigid screen structure.

75 Preferably the screen is provided with handles 41 and 42 upon the lower side and end respectively to enable the screen to be easily manipulated.

Desirably a spring 43 is placed in the run which is not ~~accessed~~ to engage the edge of 80 the sash and force the same into frictional engagement with the other run, so that the sash may be retained in elevated position. This spring desirably is located at some distance above normal position.

85 The advantages of the present invention over the usual screen construction will be obvious. In usual screen construction, one of the pair of runs is provided with a longer tongue and a deeper groove than those of the other runs and a spring is inserted either in the bottom of the groove or in the tongue which serves to force the other run members firmly into engagement.

When it is desired to remove the screen in such construction, 90 the sash is forced toward the runs having the deeper tongue and grooves until the tongue is disengaged from the groove at the opposite end of the sash when it may be swung laterally and removed. In such screen con-

95 structions, however, a heavy pressure against the side of the screen such as produced by a child pushing against the screen will frequently force the screen from its position and cause the same to fall out. In the pres-

100 ent construction, the necessity for such springs is entirely eliminated and a screen construction produced in which there is a positive locking of the screen against side- 105 wise movement of the screen when it is in closed position or in any open position pro-

110 vided the latch remains in place. Furthermore, the present construction permits a looseness of the screen in its ways to enable 115 it to fit upon the bottom of a sash which has settled slightly without leaving any space through which flies and other insects can enter the house.

120 It will thus be seen that my invention contemplates not only an assembled screen construction comprising special forms of runs which will permit the screen to be readily removed from the window frame and re-

125 placed, but also contemplates the production of various specially formed run members and screen members which may be sold sepa-

130 rately to the builder or the occupant of the house and which may be assembled by him to provide a removable screen construction for any size of window frame.

It will be understood that the specific embodiment of the invention herein disclosed is illustrative and not restrictive and that various modifications in form, construction and arrangement of parts made within the spirit and scope of the following claims.

Having thus described my invention, what I claim as new, and desire to secure by Letters Patent, is:

- 10 1. A window screen construction comprising a window frame and a sash, co-operating runs on said frame and sash each having complementary tongued and grooved members, one of the said tongues and the groove wall of the cooperating grooved member being provided with recesses so spaced and positioned as to permit the remaining portions of the tongue and recessed groove wall to pass through said respective recesses only when the sash is raised a predetermined distance from closed position, and swing about the other tongue as a pivot.
- 15 2. A window screen construction comprising a window frame and a sash, co-operating runs on said frame and sash each having complementary tongued and grooved members, one of the said tongues and the groove wall of the cooperating grooved member being provided with recesses so spaced and positioned as to permit the remaining portions of the tongue and recessed groove wall to pass through said respective recesses only when the sash is raised a predetermined distance from closed position, and swing about the other tongue as a pivot.
- 20 3. A window screen construction comprising a window frame and a sash, co-operating runs on said frame and sash each having complementary tongued and grooved members, one of the said tongues and the groove wall of the cooperating grooved member being provided with recesses so spaced and positioned as to permit the remaining portions of the tongue and recessed groove wall to pass through said respective recesses only when the sash is raised a predetermined distance from closed position, and swing about the other tongue as a pivot.
- 25 4. A window screen construction comprising a window frame and a sash, co-operating runs on said frame and sash each having complementary tongued and grooved members, one of the said tongues and the groove wall of the cooperating grooved member being provided with recesses so spaced and positioned as to permit the remaining portions of the tongue and recessed groove wall to pass through said respective recesses only when the sash is raised a predetermined distance from closed position, and swing about the other tongue as a pivot.
- 30 5. A window screen construction comprising a window frame and a rectangular screen sash, complementary run members secured respectively to the sides of said frame and ends of said sash, said runs having interengaging tongues and grooves and recesses in the tongue of one of said members and in one wall of the complementary grooved member so positioned as to permit the run member to be disengaged by lateral swinging movement about the other tongue as a pivot when the sash is raised a predetermined distance from closed position.
- 35 6. A window screen construction comprising a window frame and a rectangular screen sash, complementary run members secured respectively to the sides of said frame and ends of said sash, said runs having interengaging tongues and grooves, spaced recesses in the tongue of one of said members and in one wall of its complementary grooved member so located as to permit the run members to be disengaged by lateral swinging movement about the other tongue as a pivot when the sash is raised a predetermined distance from closed position, the thickness of the recessed tongued run being greater at one side of the tongue than upon the other side of said tongue and the walls of said co-operating grooved run having thicknesses complementary to the sides of said tongued run, whereby said recesses will be wholly covered when the screen is in closed position.
- 40 7. An article of manufacture, complementary run members for window screens having respectively a tongue and a groove, said members being adapted for attachment to a window frame and window screen frame respectively, the tongue and one wall of the groove being provided with complementary recesses so spaced as to permit the section of the tongue intermediate of its recesses to pass laterally through the recess in the wall of said groove and the sections of the grooved wall intermediate of its recesses to pass through the recesses in said tongue.
- 45 8. A window screen construction comprising a window frame and a sash, co-operating runs on said frame and sash having complementary interengaging tongued and grooved members, the tongue of one of said runs and one wall of the complementary grooved run being provided with recesses so placed and positioned as to permit the remaining portions of the tongue and recessed
- 50 9. A window screen construction comprising a window frame and a sash, co-operating runs on said frame and sash having complementary interengaging tongued and grooved members, the tongue of one of said runs and one wall of the complementary grooved run being provided with recesses so placed and positioned as to permit the remaining portions of the tongue and recessed
- 55 10. A window screen construction comprising a window frame and a sash, co-operating runs on said frame and sash having complementary interengaging tongued and grooved members, the tongue of one of said runs and one wall of the complementary grooved run being provided with recesses so placed and positioned as to permit the remaining portions of the tongue and recessed
- 60 11. A window screen construction comprising a window frame and a sash, co-operating runs on said frame and sash having complementary interengaging tongued and grooved members, the tongue of one of said runs and one wall of the complementary grooved run being provided with recesses so placed and positioned as to permit the remaining portions of the tongue and recessed
- 65 12. A window screen construction comprising a window frame and a sash, co-operating runs on said frame and sash having complementary interengaging tongued and grooved members, the tongue of one of said runs and one wall of the complementary grooved run being provided with recesses so placed and positioned as to permit the remaining portions of the tongue and recessed

groove wall to pass through the said respective recesses when the sash is raised to a predetermined distance from closed position, a plate countersunk in one of said runs extending beneath the interengaging member of said run, a guide pivotally mounted on said plate having a wall normally forming a continuation of the wall of said run across

the recess therein but adapted to be swung aside to permit detachment of the interengaging run member and the removal of said sash. 10

In testimony whereof, I have signed my name to this specification.

WILLIAM H. J. FITZGERALD.
